United States Patent

Des. 240,139
Patented June 1, 1976

240,139

LIGHTER

Guy Neyret, Francheville, Rhone, France, assignor to
Etablissements Genoud & Cie, Venissieux, Rhone,
France

Filed Aug. 30, 1974, Ser. No. 502,228

Claims priority, application France Mar. 13, 1974

Term of patent 14 years

Int. Cl. D27—02

U.S. Cl. D27—42

FIG.1

FIG.2

FIG.3

FIG.4

FIG.5

FIG.6

FIG. 1 is a top perspective view of a lighter showing my new design;

FIG. 2 is a side elevational view thereof;

FIG. 3 is a side elevational view thereof from the side opposite that shown in FIG. 2;

FIG. 4 is a top plan view thereof;

FIG. 5 is an end elevational view thereof from the left of FIG. 2; and

FIG. 6 is an end elevational view thereof from the left of FIG. 3.

The bottom of the lighter is plain.

I claim:

The ornamental design for a lighter, as shown and described.
